COMBINATION FOLDING TABLE AND BLACKBOARD

Axel H. Burkeman, Des Moines, Iowa

Application September 25, 1944, Serial No. 555,708

2 Claims. (Cl. 35—62)

My invention relates to improvements in combined folding tables and blackboards and wherein one side of the table top is a blackboard.

The objects of my improvement are: first, to provide a table having a top comprising a hingedly attached frame and a panel pivoted to the frame, one side of the panel being a blackboard; second, to provide a table having a top comprising a hingedly attached frame and a panel pivoted to the frame and serving as a support for the frame when the table top is open and the blackboard is in an operative position; and third, to provide a table having a top comprising a hingedly attached frame and a panel pivoted to the frame, one side of the panel being a blackboard and a chalk rail on the panel affording a support for the panel when the top is closed in the plane of the frame and also affording a support for the panel when the top is open and the blackboard is in an operative position.

Other objects of the invention will be apparent from the following description, reference being had to the drawings.

To the above end, generally stated, the invention consists of the novel construction and arrangement of parts hereinafter described and defined in the claims.

In the accompanying drawings, which illustrate the invention, like characters indicate like parts throughout the several views.

Referring to the drawings:

Fig. 1 is a front elevation of the table;

Fig. 2 is a plan view of the table;

Fig. 3 is an end elevation of the table, some parts being broken away;

Fig. 4 is a view principally in longitudinal section taken on the line 4—4 of Fig. 3 and showing the legs folded;

Fig. 5 is a view in transverse section taken on the line 5—5 of Fig. 4;

Fig. 6 is a view principally in front elevation showing the table top open and the blackboard in an operative position, some parts being broken away and sectioned; and

Fig. 7 is a view in transverse section taken on the line 7—7 of Fig. 6.

The rectangular body of the table comprises a pair of side members 8, a pair of end members 9 and a bottom member 10. These members 8, 9 and 10 form, within the body of the table, a compartment 11. At each end of the table body is a pair of legs 12 pivoted at 13 to the side members 8. The legs 12, of each pair, are rigidly connected by a cross-tie bar 14. By reference to Fig. 1, it will be noted that the pivots 13 of the

left-hand pair of legs 12 are higher than the pivots 13 for the other pair of said legs. This arrangement of the pivots 13 permits the left-hand pair of legs 12 to be folded inwardly onto or substantially onto the bottom member 10, see Fig. 5, and it also permits the right-hand pair of legs 12 to be folded directly under the first noted pair of legs. The legs 12 extend considerably above their pivots 13 for engagement with the end members 9 for limiting the outward swinging movement of said legs and stop the same in upright positions. Turn-buttons 15 pivoted to the end members 9 for overlapping engagement with the cross-bars 14, are provided for holding the pairs of legs 12 against inward folding movement.

The top of the table includes a rectangular frame 16 comprising side members 17 and 18 and end members 19. The side member 18 extends between the end members 19, at their respective ends, and is pivoted thereto, as indicated at 20. This table top further includes a panel 21 rigidly secured at one of its longitudinal edge portions to the pivoted side member 18 for swinging movement into and out of the plane of the frame 16.

Looking at the table top in another way, the frame 16 may be considered as comprising the side member 17 and the end members 19 and to which end members 19 the panel 21 is pivoted.

Hinges 22 connect the frame member 17 to the rear side member 8 of the table body and attach the table top to said body for opening and closing movements. The under side of the panel 21, when the table top is closed, is a blackboard 23. A chalk rail 24 is secured to the panel 21 at its free longitudinal edge portion. This chalk rail 24, on its back, is rabbeted to form a stop shoulder 25.

When the table top is closed, its frame 16 rests on the upper edges of the body side members 8 and end members 9, see Fig. 5. Also at this time the shoulder 25 of the chalk rail 24 rests on the rear side member 8 and supports the panel 21 within the plane of the frame 16. To place the

blackboard 23 in an operative position, the table top is raised and the panel 21 at its lower end is swung forwardly to bring said panel into a rearwardly inclined position. The table top is thus held in its open position by placing the chalk rail 24 into a flute 26 in the upper edge of the front side member 8 of the table body, see Fig. 7.

When the table top is closed, it affords a closure for the compartment 11.

The drawings illustrate a commercial form of the invention, but it will be understood that the

same is capable of certain modifications as to details of construction, arrangement and combination of parts within the scope of the invention herein disclosed.

What I claim is:

1. A table having a rectilinear body comprising front, back, side and bottom members affording an open top compartment, a top for the table comprising a U-frame and a panel, the transverse member of the frame being hinged to the back member of the body and resting on said member when the top is closed, the arms of the frame being outward of the side members of the body, said panel, when the top is closed, lies substantially in the plane of the frame and being pivoted at its front corner portions to the free end portions of the arms of the frame for outward swinging movement from the under side of the frame when the top is open, the front portion of the panel resting on the front member of the body when the top is closed and supporting the arms of the frame at their outer end portions, and means for supporting the panel at its inner edge portion when the top is closed.

2. A table having a rectilinear body comprising front, back, side and bottom members afford-

ing an open top compartment, a top for the table comprising a U-frame and a panel, the transverse member of the frame being hinged to the back member of the body and resting on said member when the top is closed, the arms of the frame being outward of the side members of the body, said panel, when the top is closed, lying substantially in the plane of the frame and being pivoted at its front corner portions to the free end portions of the arms of the frame for outward swinging movement from the under side of the frame when the top is open, the front portion of the panel resting on the front member of the body when the top is closed and supporting the arms of the frame at their outer end portions, and a chalk rail on the free edge portion of the panel and extending thereunder when the top is closed, said chalk rail having a shoulder that rests on the back member of the body when the top is closed, and supports the panel therefrom, the front member of the body having a flute in which the chalk rail rests when the cover is open and holding the top with the frame forwardly inclined and the panel rearwardly inclined.

AXEL H. BURKEMAN.
